UNITED STATES PATENT OFFICE.

JOHN HAMILTON BROWN, OF BOSTON, MASSACHUSETTS, ASSIGNOR TO
HIMSELF AND JAMES E. FARWELL, OF SAME PLACE.

MACHINE FOR NAILING SHOES

Specification forming part of Letters Patent No. 40,880, dated December 8, 1863.

To all whom it may concern:

Be it known that I, JOHN HAMILTON BROWN, a resident of Boston, in the county of Suffolk and State of Massachusetts, have invented a new and useful or Improved Machine for Nailing Shoes; and I do hereby declare the same to be fully described in the following specification, and represented in the accompanying drawings, of which—

Figure 1 is a top view, Fig. 2 a front side elevation, Fig. 3 a longitudinal section, Fig. 4 a horizontal section, Fig. 5 a front end elevation, and Fig. 6 a rear end elevation, of it. Fig. 7 is a horizontal section taken through the ratchet and pawl of the nail strip carrier. Fig. 8 is a transverse and vertical section of the handle, it being taken in the plane of the rear face of the stock.

My improved hand-machine for nailing shoe-soles not only has its shear or cutter arranged with respect to the nail-driver and nail-strip carrier substantially in manner as herein-after described, but has combined with the said shear or cutter and the nail-driver a mechanism—viz., a cam and lever—which, through the downward movement of the nail-driver, will be caused to force the shear forward or against the nail-strip in a manner to sever a nail therefrom. The said machine also contains a mechanism for feeding the nail-plate along as fast as may be desirable for the separation of nails from it. The machine also contains other improvements, to be hereinafter explained.

In the drawings, A denotes a tubular handle, projecting upward from a channeled stock, B, whose inner face is furnished with a straight groove or channel, a, leading downward from the bore of the handle. The said face is also provided with a socket for the reception of a shear or cutter, C, which slides freely in a longitudinal direction, both toward, away from, and across the channel a, and has a friction-roller, b, applied within its rear part. Against the periphery of the said friction-roller a cam, c, formed on a lever, D, operates, the cam serving to force the shear forward during a depression of the lever. This lever D has its fulcrum at d, it being supported by the stock B. Furthermore the lever at its inner end is jointed to the lower end of a connecting-bar, e, whose upper end is jointed to

a nail-driver, E, which works within the handle A and the channel a. The shank or part f of the driver is tubular from its head g to its lower end, and contains a helical spring, h, whose foot rests on a stationary bearer, i, which projects upward from the stock B. The spring, by its reaction against the head of the bearer, serves to elevate the driver within the handle and stock, and this immediately after each downward movement of the driver.

The advantages of arranging the spring within the driver, and providing such spring with a bearer to work up into the shank of the driver, while the latter may be in the act of being driven downward, are that it not only enables the driver to be made of less diameter, but the spring to operate with less friction than would be the case were the spring coiled around the driver. A tubular carrier, F, for supporting the strip G, of copper or metal, from which the nails are to be cut, extends from the inner face of the stock; and at its inner end opens directly into the channel a thereof. The said carrier is furnished with a feed-roller, H, which projects therein in such manner that its periphery rests against one side of the nail-strip. A pressure-roller, I, supported by a spring, K, so operates against the opposite side of the nail-strip as to press the said strip in close contact with the feed-roller. A ratchet, l, is fixed on the shaft l of the feed-roller, and furnished with a slide-pawl, m, which is forced up to the ratchet by a spring, n. This pawl slides longitudinally within the carrier, and has a projection or cam, o, which so extends from it as to be in the path of the bar e during the downward movement of the latter. A spring, p, fixed to the outer side of the carrier, bears against the cam o and serves to move the pawl in a direction opposite to that which it may receive from the pressure of the bar e against its cam o. There is within the carrier F an auxiliary carrier or tube, L, which projects from a spring, N, arranged within the carrier. The object of the said tube L and spring N is not only to give support to the inner end of the nail-strip and enable it to move laterally under the pressure of the shear, but to restore it and the shear to their normal positions immediately after a nail may have been severed from the strip.

In operating with this machine a workman is to hold it in one hand and by its handle, he having in his other hand a hammer or a mallet. Holding the machine with the foot of stock on the part of the sole into which it may be desirable to insert a nail, he strikes with the hammer or mallet a blow on the top of the nail driver, which, being driven downward within the handle and stock, will cause the shear to be advanced against the nail-strip, and to sever therefrom a nail or that part of the said strip which may project into the channel α . As soon as this may have taken place, the nail, by the further descent of the driver, will be forced downward through the said channel and into the sole. In the meantime the pawl of the ratchet of the feed-wheel will be pressed back and will slip on the teeth of the latter. During the elevation of the driver by the helical spring within it, which will follow, the nail-strip and the shear will not only be forced into their normal positions by the reaction of the spring N , but the nail-strip will be afterward advanced into the channel α , this latter movement of the nail-strip being caused by the reaction of the spring p against the pawl of the ratchet, the same producing a rotary movement of the feed-wheel, such as will cause it to advance the strip into the channel α .

The above-described hand-machine is an automatic one, in so far as by a blow on the driver, by which such driver may be forced downward, not only will a nail be separated from the strip and be driven out of the machine and into a sole, but on elevation of the driver by its spring the strip and shear will

be moved laterally, and the strip will be advanced in manner as hereinbefore described.

I claim—

1. The improved machine as not only having its shear or cutter arranged with respect to the nail-driver and nail-strip carrier, substantially in manner as described, but as having combined with the shear and nail-driver a mechanism—viz., the lever D and cam c , or the mechanical equivalent thereof—which, through or by the downward movement of the said driver, shall be caused to force the shear forward against the nail-strip in a manner to cause a nail by the conjoint action of the channel α and the said shear to be separated from the strip.

2. The improved machine as not only so made, but as provided with a feeding mechanism, constructed, arranged, and applied to the nail-strip carrier, substantially as and so as to be operated by means as described.

3. The arrangement and combination of the spring N , either with or without the auxiliary carrier L , with the nail carrier, the channeled stock, and the shear, made to operate with such stock, as specified.

4. I do not claim the combination of a spring with the nail-driver for the purpose of elevating it within the handle; but I claim, in the nailing-machine, not only the arrangement of the spring within the driver, but its combination with a bearer to work within such driver, substantially as specified.

J. H. BROWN.
